Term of patent 14 years

Int. Cl. D12—07

U.S. Cl. D71—1 J

FIG. 1

FIG. 1 is a left-hand side elevation of a helicopter fuselage according to the invention;

FIG. 2 is a front view of FIG. 1; and

FIG. 3 is a top view of FIG. 1.

The right-hand side elevation of the helicopter is substantially the mirror image of FIG. 1 and the broken line disclosure is for illustrative purposes only.

I claim:

The ornamental design for a helicopter fuselage, as shown and described.
